UNITED STATES PATENT OFFICE.

THEODORE H. SCHROR, OF CALEDONIA, NEW YORK.

RING-MOUNTING.

1,188,841.

Specification of Letters Patent. Patented June 27, 1916.

Application filed November 24, 1915. Serial No. 63,181.

To all whom it may concern:

Be it known that I, THEODORE H. SCHROR, a citizen of the United States, residing at Caledonia, in the county of Livingston and 5 State of New York, have invented certain new and useful Improvements in Ring-Mountings, of which the following is a specification.

My invention relates to improvements in 10 ring mountings and refers particularly to mountings for artificial pearls or other hollow gems.

An object of my invention is the provision of a mounting in which the artificial pearl 15 or gem is held securely and firmly in place, thus preventing the artificial pearl or gem from being lost, and which presents an ornamental appearance.

A further object of my invention is the 20 provision of a substantial, durable, and otherwise more desirable setting for artificial pearls and other gems, which can be used by any skilled person.

With these and other objects in view, my 25 invention consists of a ring mounting embodying novel features of construction, combination and arrangement of parts substantially as described and particularly defined by the claims.

30 In order that the detailed construction, features of merit and its many advantages may be fully understood, I have shown in the accompanying drawing a ring mounting constructed in accordance with and embodying my invention, it being understood that 35 I do not limit its use to ring mountings and any changes or alterations may be made which fall within the spirit and scope of my claims.

40 Figure 1 is an elevation of the ring with the crown broken away to show the manner of securing the pearl. Fig. 2 is a similar view, the pearl being shown in section to clearly show important details, and Fig. 3 45 is a detail view of the split pin for securing the pearl in the crown of the ring.

In carrying out my invention, I employ the ordinary ring mounting A, having the usual crown or prongs B, which in the old 50 manner of setting bind against the gem and

thus hold it in place, but in my invention I employ in connection with the ring A, the pin C, having the head D, fitting in the counter-bored recess E, said pin C, having its shank passing through the opening G and 55 terminating in the split or pronged portion H.

In the drawings, I have illustrated my invention in connection with an imitation pearl J, of hollow construction, having the 60 opening K, to receive the prongs H, which are spread apart as shown in Fig. 2, and when in this condition and embedded in the cement L, they serve to lock the pearl in proper place in the crown of the ring. The 65 prongs on the pin are first sprung apart, then their ends squeezed together and inserted in the gem, the prongs naturally springing apart after entrance into the gem and in that position are secured by the hardening of the cement, effecting the perfect 70 securing of the gem. After the gem has been set in this manner, the head D, of the pin C, is soldered in the recess E, thus securely and firmly setting the gem and preventing 75 any possible chance of the gem becoming loose in the mounting or lost.

Thus it will be seen that I provide a mounting which will be small, neat and attractive in appearance, which will securely 80 retain the gem; and one which can be used as a ring mounting or in fact in any place where a mounting of this character will be desirable.

I claim:—

1. In combination with a finger ring, of a mounting for any hollow gem, consisting of a crown portion having a cylindrical opening on its under side and having a counterbored recess in the bottom of said 90 opening, a pin having its head soldered in said recess, said pin having its end split, a hollow gem, having an opening to receive said pin, said hollow gem being filled with cement to secure the split ends of said pin. 95

2. A mounting of the character described consisting of a crown portion having an opening leading to an enlarged recess therethrough and in the bottom of said opening forming a seat, a hollow gem fitting in the 100

crown and having an opening alining with the opening of the crown, and a pin disposed in said opening with a lower head fitting in the said seat and an upper split 5 end forming a pair of prongs entering the opening of the gem and adapted to be spread to secure the gem in the crown.

In testimony whereof I affix my signature in the presence of two witnesses.

THEODORE H. SCHROR.
